UNITED STATES PATENT OFFICE.

JACOB BOOTH, OF REYNOLDSVILLE, PENNSYLVANIA.

RAILWAY-TIE.

SPECIFICATION forming part of Letters Patent No. 761,575, dated May 31, 1904.

Application filed December 13, 1902. Serial No. 135,073. (No model.)

To all whom it may concern:

Be it known that I, JACOB BOOTH, a citizen of the United States, and a resident of Reynoldsville, in the county of Jefferson and State 5 of Pennsylvania, have made a certain new and useful Invention in Railway-Ties; and I declare the following to be a full, clear, and exact description of the same, such as will enable others skilled in the art to which it appertains 10 to make and use the invention, reference being had to the accompanying drawings, and to letters of reference marked thereon, which form a part of this specification.

Figure 1 is a side elevation of my invention 15 as applied. Fig. 2 is a similar view illustrating a modified form of the invention. Fig. 3 is a plan view of one end portion of the tie with overlying parts removed. Fig. 4 is a fragmentary plan view illustrating the use of 20 reversible blocks $w w'$. Fig. 5 is a section on the line 5 5, Fig. 1.

The invention relates to improvements in railway-ties; and it consists in the novel construction and combinations of parts, as hereinafter set forth.

In the accompanying drawings, illustrating the invention, the letter a designates a railroad-rail, and b the compound tie. This tie is composed of a body portion of brick or cement 30 blocks or sections c , a top or surface plate d , vertical bolts e , inset bottom bolt-plates f , and a longitudinal tie-bolt g . The blocks or sections c extend individually the height of the tie. The surface plate is formed with a recess-bearing h near each end to receive the base of the rail. This bearing portion is made the full thickness of the plate, and the brick or cement block c' , upon which the bearing portion of the plate rests, is shorter than the 35 other bricks of the body, being so made to accommodate the bearing, while its lower end is flush with the bottoms of the other bricks. The brick body is made secure and solid by means of the longitudinal tie-bolt k , which 40 extends from end to end of the body, its head l and nut m bearing against the end plates p . The rails are held in place in their bearings by means of the outer and inner clamp-plates 45 q and r , the former being usually made in loop form and serving as a joint-plate when running. These outer loop-clamps q are

formed with oblique bracing-arms t , having downturned end portions which engage transverse bearing-shoulders v of the surface plate and are thereby held firmly in position. The 55 clamps are secured by means of the vertical bolts e , which pass through the body and through the bottom bearing-plates f and are fastened by suitable nuts. As the body-bricks are held securely by the longitudinal tie-rod 60 these bottom plates may be made short, being, however, long enough to receive the ends of the vertical bolts. These bottom plates are located under the rail-bearings of the surface plate. 65

Sometimes spikes may be used in connection with the surface plate to hold the clamps. Where the ties are to be used on curves, the bearing-recesses should be made wide enough for wedging up on the inside. In the body of 70 the tie hollow brick may be used, except under the rail-bearings, and in this way the tie may be made lighter and its transportation facilitated.

A pad of cork, wood, or the like may be 75 used between the iron surface plate and the bed of the rail.

Reversible blocks $w w'$ may be used to adjust the rails toward each other when worn on their inner edges by the rail-flange of the 80 wheel.

Having described this invention, what I claim, and desire to secure by Letters Patent, is—

A compound railroad-tie comprising the 85 brick or cement body-sections extending individually the height of the tie, the top plate having the transverse bearing-shoulders, the short inset bottom plates, the vertical tie-bolts or spikes connecting said top and bottom plates, the clamp-plates for the rails, the outside of said clamp-plates having downturned end portions in engagement with said bearing-shoulders, the end plates and the longitudinal tie-bolt, substantially as specified. 90 95

In testimony whereof I affix my signature in presence of two witnesses.

JACOB BOOTH.
